UNITED STATES PATENT OFFICE.

CESARE BARBIERI, OF NEW YORK, N. Y., ASSIGNOR TO THE VORTEX MANUFACTURING COMPANY, A CORPORATION OF ILLINOIS.

HOLDER AND METHOD OF TRANSFERRING STACKED SUNDAE CUPS FROM CUP-STACKING MACHINES INTO CARTONS.

Application filed September 25, 1922. Serial No. 590,266.

To all whom it may concern:

Be it known that I, CESARE BARBIERI, a subject of the King of Italy, and a resident of the city of New York, in the county of New York and State of New York, have invented certain new and useful Improvements in a Holder and Method of Transferring Stacked Sundae Cups from Cup-Stacking Machines into Cartons; and I do hereby declare that the following is a full, clear, and exact description of the same, reference being had to the accompanying drawings and to the numerals of reference marked thereon, which form a part of this specification.

Considerable difficulty has been encountered in removing stacked conical sundae cups from the stacking attachments of cup-forming machines, particularly with cups formed from circular blanks which, when formed, are each radially creased on divergent lines from the center to the periphery to form a triangular folder portion or lap acting to open up the cup, thereby causing the same to spring away from a cup immediately therebelow and thus making it difficult to nest the cups one within the other in a straight stack.

This invention relates to an improved holder adapted to remove a stack of conical folded cups from a cup-stacking machine attachment and then deliver the same into cartons without permitting the stack to become distorted due to the springing effect of the lapped portions of the cups.

It is an object of this invention to provide a holder for removing a stack of paper cups from a cup-forming machine.

It is also an object of the invention to provide a holder whereby stacked cups having a tendency to spring away from one another to distort the stack may be transferred from a cup-forming machine into a carton without permitting the stack to become distorted.

It is a further object of the invention to provide a holder so formed to permit the same to be engaged on a stack of formed cups while they are held in stacked relation in a cup-forming machine stacking attachment.

It is furthermore an object of this invention to provide a method whereby formed

paper cups assembled in a stacking attachment may be removed in stacked relation and transferred into a carton by means of an improved holder.

It is an important object of this invention to provide a holder so formed to permit removal of a stack of paper sundae cups from a stacking device into a carton for shipment without permitting distortion of the stack of cups which ordinarily are difficult to handle without a holder, inasmuch as the construction of the paper sundae cups is such that a stack of any considerable height readily becomes distorted, making it difficult to handle.

Other and further important objects of this invention will be apparent from the disclosures in the specification and the accompanying drawings.

The invention (in a preferred form) is illustrated in the drawings and hereinafter more fully described.

On the drawings:

Figure 1 is a front elevation of a holder embodying the principles of this invention.

Figure 2 is a top plan view thereof.

Figure 3 is a longitudinal section taken on line 3—3 of Figure 2.

Figure 4 is a rear elevation of the holder placed in position to remove a stack of cups from a cup-forming machine stacking attachment.

Figure 5 is a section taken on line 5—5 of Figure 4 showing the stack of cups in elevation.

As shown on the drawings:

The holder comprises a cylindrical metal shell or tube 1 open at its upper end and having a conical base flange 2 at the lower or other end. The conical base flange 2 is cut away at one side to afford an opening 3 which registers with a restricted opening 4 at the lower end of the front side of the tube 1. The tube 1 has a longitudinal strip cut out of the front side thereof to afford a longitudinal opening 5, the lower end of which is restricted by means of extensions or ears 8 and connects up with the opening 4. Secured to the back of the tube 1 are two handles 7 disposed near the upper and lower ends of said tube.

Figure 4 illustrates a fragmentary elevation of a stacking attachment adapted for

use in connection with a paper cup-forming machine (not shown) but of a type similar to that covered in my pending application for patent for a "multiple automatic folding machine", filed September 10, 1921, Serial No. 499,614. The stacking attachment broadly embraces a driving shaft 9 on which a bevel gear 10 is fixed to mesh with a bevel gear 11 to drive a feed screw 12. One end of a supporting arm 13 is engaged on the feed screw and is adapted to be automatically lowered predetermined amounts each time a cup is deposited thereon from the cup-forming machine. Supported in the outer end of the arm 13 is a conical cup receiving socket 14. Vertical guard bars 15 are provided to hold the sundae cups 16 nested one within the other in a straight stack as shown in Figure 5. A swinging cup retaining guard 17 is also provided for holding the cups properly stacked. When the stack of formed cups supported on the socket 14 has reached a predetermined height and is held straight by the guards 15 and 17, the improved holder 1 is adapted to be used to permit the stack of cups to be removed from the socket 14 and placed in a carton without any danger of the stack of cups becoming distorted by bulging out at the sides due to the peculiar construction of the spring folds in the paper cups. The holder is engaged by the handles 7 and one edge of the opening 5 is placed against one side of the stack after the movable guard 17 is swung out of the way into the position illustrated in Figure 4. The holder 1 is then pushed into place around the stack of cups with the holder flange 2 disposed slightly below the conical socket 14 to permit the holder to be engaged around the stack of cups above the restricted position shown in Figure 5 with the holder flange 2 in contact with the outer surface of the lowermost cup 16. The stack of cups is now lifted from the socket 14 by means of the holder, the walls of which act to hold the cups in place nested one within the other without danger of the stack bulging outwardly at the sides or otherwise becoming distorted. With the stack of cups positioned within the holder, the holder is turned into a horizontal position to permit the stack of cups to be pushed longitudinally away from the holder flange 2 and then out of the holder opening 5 and deposited in a suitable container or carton of a size sufficient to hold the cups in stacked relation ready for storage or shipment as desired. I am aware that numerous details of construction may be varied through a wide range without departing from the principles of this invention, and I therefore do not purpose limiting the patent granted otherwise than necessitated by the prior art.

I claim as my invention:

1. A stacked cup holder comprising a cylindrical tube having a longitudinal opening therein restricted at one end, and a conical flange at one end of said tube having an opening therein registering with the restricted end of the tube opening.
2. A stacked cup holder comprising a tube having a longitudinal opening therein restricted at one end, handles on said tube, and a conical flange secured to one end of said tube and having an opening therein registering with the restricted portion of the tube opening.
3. A stacked cup holder comprising a tube having a longitudinal opening therein, ears integrally formed at one end of the tube to afford a restricted opening connecting up with the tube opening, handles secured to said tube, and an inclined flange at one end of said tube having an opening therein registering with said restricted opening.
4. A stacked cup holder, comprising a longitudinally slotted tube tapered at one end, said slot extending through said tapered end.
5. A stacked cup holder, comprising a tube having a longitudinal slot therein restricted at one end.
6. A stacked cup holder comprising a tube provided with a tapered flange at one end, said tube and flange cut away to afford a longitudinal opening restricted at the flange.
7. A cup holder comprising a slotted tube, an inwardly inclined slotted flange on one end thereof, and handles on said tube.
8. The combination with a receptacle stacking attachment, of a holder adapted to be engaged on a stack of receptacles in said attachment to permit said stack to be removed.
9. The combination with a receptacle stacking attachment, of a holder adapted to remove a stack of receptacles from said attachment and to retain said stack against distortion.
10. The combination with a receptacle stacking attachment, of a holder adapted to remove a stack of receptacles from said attachment, to retain said stack against distortion and to discharge said stack into a carton.
11. The combination with a paper cup stacking machine, of a slotted holder adapted to be engaged on a stack of cups in said machine, and handles on said holder to permit the holder to be lifted to remove the stack of cups from the machine held in nested relation by said holder.
12. The method of transferring stacked receptacles from a stacking machine, consisting in applying a holder to a stack of receptacles in the machine, then removing the

holder together with the stack of receptacles, and then transferring the stack of receptacles from the holder directly into a receptacle.

- 5 13. The method of transferring stacked receptacles from a stacking machine, consisting in engaging a slotted holder on a stack of receptacles in the machine, then lifting the holder to permit the stack to be
10 removed from the machine, and then turn-

ing the holder into a position to permit the stack to be transferred into a carton.

In testimony whereof I have hereunto subscribed my name in the presence of two subscribing witnesses.

CESARE BARBIERI.
